APPARATUS FOR USE IN APPLYING
PRESSURE TO SHOE BOTTOMSErastus E. Winkley, Lynn, Mass., assignor to
United Shoe Machinery Corporation, Paterson,
N. J., a corporation of New Jersey

Application December 3, 1937, Serial No. 177,954

24 Claims. (Cl. 12—33)

This invention relates to apparatus for use in applying pressure to shoe bottoms and is illustrated herein with particular reference to its utility in cement attaching soles to shoes.

5 In cement attaching soles to shoe bottoms it is desirable to have the work engaging surface of the pressure applying member, usually a yieldable pad, conform as closely as possible to the longitudinal contour of the shoe bottom before 10 pressure is applied since this facilitates locating the sole and shoe in the proper position on the pad and also makes it unnecessary to deform or distort the pad an unreasonable amount to insure that substantially the same pressure will be 15 applied to all portions of the shoe bottom. It is also desirable after obtaining an initial conformation of the pad to the contour of the shoe bottom to have it capable of being even more closely conformed to such contour under pressure 20 from the shoe.

An object of the present invention is to provide an improved apparatus involving a novel organization of parts for accomplishing the above results.

25 To this end and in accordance with one feature of the invention, there is provided, in apparatus having a pad for applying pressure to shoe bottom, separate members for holding and supporting the pad, means for maintaining the pad 30 holding members in operative position while permitting movement thereof in the longitudinal median plane of a shoe on the pad, and a fulcrum for each of said members, said fulcrums being adjustable lengthwise of the pad to vary 35 the positions of the axes about which said members move in said plane. As herein illustrated, the pad supporting or holding members may rock or swing about the fulcrums provided by abutments and the pad holding members are so 40 mounted that adjustment of the fulcrums or abutments lengthwise of the pad permits swinging movement of the pad holding members into any desired angular position.

The adjustment of the fulcrums lengthwise of 45 the pad is accomplished in the present illustrative embodiment of the invention simultaneously by a single screw having right and left threads acting respectively on each of the abutments providing the fulcrums, so that when the screw is 50 rotated the abutments will be moved simultaneously toward or away from each other lengthwise of the pad to shift the fulcrums and thereby permit the pad holding members to be rocked into different angular positions. This rocking or 55 swinging arrangement of the pad holding mem-

bers about the abutments upon which they are supported also permits these members to be further positioned at the proper angles by pressure of the sole and shoe against the pad. By this arrangement the pad may not only be initially 5 conformed to the longitudinal contour of the shoe bottom but, if desired, the amounts of pressure applied to different portions of the sole and shoe may be controlled and varied at will. As herein illustrated, the mechanism permitting 10 rocking movement of the pad holding and supporting members about the abutments is provided with friction means for initially maintaining 15 these members in any angular position into which they may be moved.

In accordance with another feature of the invention, there is provided improved means for causing the pad to be positioned automatically in accordance with the transverse angle of the portion of the shoe bottom engaging the pad. As 20 herein illustrated, the pad of the present apparatus is caused to conform to the transverse angle of the forepart of the shoe bottom under pressure of the shoe by an insert located between the pad and its holding or supporting member, this 25 insert having a bottom surface which is convex transversely of the pad. When pressure is applied to the sole and shoe, the forward portion of the pad will be tipped transversely of the apparatus by rocking movement of the insert until 30 said portion is located at the same transverse angle as the plane of the forepart of the shoe bottom.

With the above and other objects and features 35 in view, the invention will now be described with reference to the accompanying drawings and will thereafter be pointed out in the claims.

Fig. 7 is a transverse sectional view taken on the line VII—VII of Fig. 5.

The apparatus of the present invention for use in applying pressure to shoe bottoms is illustrated herein, by way of example, in connection with a cement sole-attaching machine of the type disclosed in Letters Patent of the United States No. 2,047,185, granted July 14, 1936, on an application filed in the name of Milton H. Ballard et al. It should be understood, however, that the apparatus is not confined in its utility to a machine of that type but may be used with equal advantages on other types of machines for applying pressure to shoe bottoms such, for example, as a sole laying machine.

The apparatus comprises a base plate 10, herein illustrated as secured by screws 14 to a table or bracket 12 forming a portion of a rotary turret on the cement sole-attaching machine. At its right-hand end, as viewed in Fig. 1, the plate 10 is provided with upstanding lugs 16 to each of which is pivotally secured by a shoulder screw 18 a relatively long link 20 which extends lengthwise of the plate 10 for substantially its full length. The links 20 are pivotally secured at their opposite ends by screws 24 to a pair of lugs 22 extending downwardly from a flat rectangular member 26 forming a part of mechanism for holding and supporting the pad of the pressure applying apparatus.

Above the links 20 on the lugs 22 are pivotally secured by a transverse shaft 28 (Figs. 1 and 4) another pair of relatively long links 30 which extend lengthwise of the base 10 toward its right-hand end and are pivotally connected by another transverse shaft 32 to downwardly projecting lugs 34 formed on the lower side of another flat member 36 of substantially the same shape as the member 26. As stated above, the members 26 and 36 hold and support the pad with which the apparatus is provided against pressure of a sole and shoe during the cement attaching or sole laying operation, and these members are provided with means for holding the pad thereon and with further means for causing the work engaging surface of the pad to be conformed substantially to the shape of the shoe bottom.

The pad conforming means, as herein illustrated, comprises an insert 38 resting on the pad holding member 26 at the forward portion of the apparatus, this insert having a lower surface 40 which is convex transversely or widthwise of the apparatus, as shown in Fig. 6. The insert 38 may be formed of one or two sections (herein shown as two), and it has a concave upper surface 42 which may be substantially complementary to the desired shape of the tread surface of the forepart of a finished shoe or, if desired, may be more concave than is required for a shoe bottom so that pressure of the apparatus against the sole and shoe will be greater at their marginal portions than at their central portions. The convex surface 40 of the insert 38 permits the latter to roll or rock transversely of the apparatus on the member 26 and thereby to adjust itself automatically under pressure to the transverse angle of the forepart of the shoe bottom relatively to the transverse angle of the shank and heel portions of the shoe bottom. Since the insert 38 is resting loosely on the member 26, the right-hand end of this member has a projection 44 thereon to prevent the insert from sliding rearwardly of the apparatus off the pad holding member during the operation thereof.

On opposite sides of the forward end of the

insert 38 are mounted a pair of upstanding straps 46 arranged for heightwise adjustment by screw-and-slot constructions 48 and having inwardly projecting portions which overlie the marginal portions of a pressure applying pad 50 and secure the left-hand end of the pad, as viewed in Figs. 1 and 2, to the insert 38. The pad 50, as herein illustrated, comprises a relatively thick layer of resilient material such as rubber which may be conformed under pressure to the shape 10 of the upper surface 42 of the insert and may also be compressed considerably under pressure.

The pad-holding and supporting member 36 at the rear portion of the apparatus is provided with an insert 52 which rests on the member 36 and bears against a shoulder 54 at its forward end. Both the insert 52 and the right-hand end of the pad 50 are secured against the member 36 by upwardly extending straps 56 which are adjustably secured to opposite sides of that member by slot-and-screw constructions 58. The straps 56, as shown in Fig. 4, have inwardly projecting portions which overlie the pad and secure it and the insert 52 against movement on the member 36. The lower surface of the insert 52 is flat but it has an upper surface 60 which is substantially complementary to the shank and heel portions of a shoe bottom except that it is provided at opposite sides of its forward portion with substantial bulges 62 (Figs. 1 and 7) arranged to force the opposite sides of the pad firmly against the shoe upper at the shank portion of the shoe and thereby to produce close-fitting sole margins at said shank portion.

In order that the pad holding and supporting members 26 and 36, and the inserts and pad carried thereby, may be supported against pressure from a sole and shoe and may still be angularly adjustable relatively to each other around their respective pairs of links 20 and 30, the members 26, 36 are supported respectively near their adjacent ends by abutment members 64 and 66 adjustably mounted on the base plate 10 and extending transversely across the full width thereof, these abutments providing fulcrums about which the members 26 and 36 can rock. At their upper portions the abutments 64 and 66 are cut away intermediate of their opposite sides to provide three upstanding ears 68 (Figs. 1 and 4), and the abutment 64 carries in these ears a transverse pin 70 held against rotation in the abutment by a set screw 72. The abutment 66 has mounted in its ears 68 a transverse pin 74 secured to the central ear by another set screw 72. Rotatably mounted on each of the transverse pins 70, 74 between the ears 68 is a plurality of rolls 76 which engage the bottom surfaces of the pad holding members 26 and 36 and, with the pivotal arrangements provided by the links 20 and 30, support the members 26 and 36 for swinging movement about their fulcrums lengthwise of the plate 10 and the pad 50 in the longitudinal median plane of a shoe mounted on the pad. Since the abutments 64, 66 are adjustable lengthwise relatively to the base plate 10 and the pad 50, the fulcrums of the members 26, 36 may be varied to permit rocking movement of these members lengthwise of the pad to locate said members in different angular positions relatively to each other.

The abutments 64 and 66 are adjusted lengthwise of the pad by a screw 78 threaded through the abutments and supported thereby, this screw being provided with right-hand threads 80 on its forward portion which act upon the abutment 75

64, and with left-hand threads 82 upon its rear portion which act upon the abutment 66 so that, when the screw is rotated, the fulcrums about which the pad holding members swing will be moved simultaneously toward or away from each other at equal speeds thereby changing the locations of the fulcrums and permitting the angular positions of the pad holding members and the pad supported thereby to be changed in accordance with the longitudinal contour of the bottom of the shoe resting on the pad 50 or, if desired, in accordance with the pressure which is to be applied to different portions of the shoe bottom.

13. The forward or left-hand end of the screw 78, as viewed in Figs. 1 and 5, has threaded thereon a spool-shaped collar 84 the reduced central portion of which rests in a vertical slot 86 in an angle plate 88 (Figs. 3 and 5) secured to the base plate 10, so that the collar 84 is confined against movement lengthwise of the pad but may be rotated relatively to the plate 88. On the extreme left-hand end of the shaft 78 is a lock nut 90 which, when it is turned against the collar 84, locks it to the shaft 78 so that manual rotation of the lock nut thereafter rotates the shaft and causes the abutments or fulcrums 64, 66 to be adjusted toward or away from each other lengthwise of the pad in the manner described. When, however, the lock nut 90 is loosened from the collar 84 the latter may be rotated in the member 86 independently of the lock nut and shaft 78 to cause the shaft to move bodily lengthwise of the pad without rotating and thereby to adjust the abutments 64 and 66 as a unit in the same direction, that is, either forwardly or rearwardly lengthwise of the pad.

It will be seen from the above that the adjustments provided by the spool-shaped collar 84 and the lock nut 90 permit the abutments 64 and 66, which serve as fulcrums about which the pad holding members 26 and 36 swing or rock lengthwise of the pad, to be adjusted simultaneously lengthwise of the pad either in the same direction or in opposite directions. Consequently, it is possible with this construction to locate the abutments and the rolls 76 in any desired position lengthwise of the pad relatively to the members 26 and 36. As illustrated in Fig. 5, the abutment 64 is located a little forwardly of the ball line of the shoe mounted on the pad whereas the abutment 66 is located substantially midway between the ball line and the heel end of the shoe. The arrangement shown causes substantially uniform pressure for each unit of the bottom area to be applied to the shank and heel portions of the shoe and a pressure to the forepart which gradually diminishes from the vicinity of the ball line to the toe end of the shoe. It will be clear, therefore, that the pressures at both the forepart and the rear portions of the shoe bottom could be varied in other ways if desired by longitudinal adjustment of the fulcrums 64 and 66.

65. After the fulcrums have been adjusted lengthwise into positions which permit the members 26 and 36 and the pad supported thereby to be located so that the sole engaging surface of the pad conforms approximately to the longitudinal contour of the shoe bottom, it is desirable to maintain the pad holding and supporting members in their positions of angular adjustment until the shoe and sole on the pad are actually under pressure. For this purpose the shaft 28 (Fig. 4) extends beyond the link 30 at the inner

side of the pad and carries a compression spring 92 which is forced against the link 30 by a nut 94. At the right-hand end of the pad, the shaft 32 also extends inwardly beyond the pad and carries a compression spring 96 which is forced against the link 30 by a nut 98. The springs 92 and 96 may be put under sufficient compression by their retaining nuts to cause the members 26 and 36 to be maintained by friction alone in whatever angular positions they may have been swung after adjustment of the abutments 64 and 66. When pressure is applied to the sole and shoe, however, the members 26 and 36 and the pad 50 can further rock about their fulcrums on the abutments into angles which coincide with those of the corresponding portions of the shoe bottom.

Although the operation of the apparatus will be apparent from the foregoing description, its use in connection with a cement sole attaching machine of the type referred to above will be reviewed for the purpose of clearness. As shown in Fig. 1, the cement sole attaching machine is provided with pressure applying members 100 and 102 for engaging respectively the forepart of a shoe A (Fig. 5), and the rear portion of a last L in the shoe. The shoe A may first be treated on its bottom surface with a suitable cement such, for example, as pyroxylin or chloroprene and it may then be mounted on the pad 50 with a sole B, the marginal portion of the upper surface of the sole having been similarly treated with cement. When the cement is in condition to cause adhesion of the parts, the operator positions the members 26 and 36, by adjustment of the abutments or fulcrums 64 and 66 through rotation of the lock nut 90, in angular positions which conform the upper surface of the pad as closely as possible to the shape of the longitudinal contour of the bottom of the shoe which is resting on the sole. If the shoe is a particularly large shoe or a particularly small shoe the operator may loosen the lock nut 90 and rotate the collar 84 to move both abutments as a unit lengthwise of the pad until they are located substantially equal distances from the opposite ends of the pad, thereby locating the abutments in similar positions relatively to their respective pad holding members 26 and 36. The operator may then screw the lock nut 90 against the collar 84 and by further rotation of the lock nut in one direction or the other rotate the screw 80 to move the abutments simultaneously toward or away from each other until each abutment is located in such a position lengthwise of the shoe that it will cause the pad holding member and pad to apply the desired pressure to different portions of the forepart and the rear portion of the shoe bottom. After the adjustments have been made, the members 26 and 36 may be caused to swing or rock about their fulcrums to conform the pad as closely as desired to the longitudinal contour of the shoe bottom, this rocking movement being permitted by the link arrangement which supports the opposite ends of the pad holding members, and these members being maintained by friction in their angular positions by the compression springs 92 and 96.

70. The pressure applying members 100, 102 of the cement sole attaching machine may now be caused to move downwardly into engagement with the last and shoe through the actuation of fluid pressure operated mechanism with which the machine is provided for pressing a sole and shoe against the pad to perform a cement sole attaching or,

if desired, a sole laying operation. As shown in Fig. 6, the inner surface 42 of the insert 38 is of such a shape that the forepart of the shoe bottom will be pressed by the pad into the desired 5 contour both lengthwise and widthwise of the shoe. Moreover, if the transverse angle of the plane of the forepart of the shoe is different from the transverse angle of the plane of the rear portion of the shoe, the insert 38 will rock trans- 10 versely of the pad until the latter conforms itself accurately to the transverse angle of said forepart. The bulges 62 at opposite sides of the shank portion of the pad will cause the sides of the pad to press firmly against the shoe upper adjacent to the shank portion of the sole, thereby 15 producing a close fitting sole margin at the shank portion of the shoe. As indicated above, as the pressure applied by the cement sole attaching machine increases, the pad holding members 26 20 and 36 may be further adjusted about the abutments 64, 66 into accurate conformity with the angles of the forepart and the shank and heel portions of the shoe bottom.

Having thus described my invention what I 25 claim as new and desire to secure by Letters Patent of the United States is:

1. An apparatus for use in applying pressure to shoe bottoms comprising a pad, separate pad holding members, a fulcrum for each of said 30 members about which each member swings, and means for adjusting said fulcrums lengthwise of the pad.

2. An apparatus for use in applying pressure to shoe bottoms comprising a pad, separate pad holding members, means for maintaining said pad holding members in operative position while permitting movement thereof in a plane extending lengthwise and heightwise of a shoe on the pad, and a fulcrum for each of said members, 35 said fulcrums being adjustable lengthwise of the pad to vary the positions of the axes about which said members move.

3. An apparatus for use in applying pressure to shoe bottoms comprising a pad, separate members for supporting the pad, means for maintaining the pad supporting members in operative position while permitting movement thereof in the longitudinal median plane of a shoe on the pad, a fulcrum for each of said members, and means 45 for adjusting said fulcrums lengthwise of the pad to vary the positions of the axes about which said supporting members move in said plane.

4. An apparatus for use in applying pressure to shoe bottoms having, in combination, a pad for 50 pressing a sole against a shoe bottom, separate members for holding different portions of the pad in operative position, means for supporting each of said members for rocking movement lengthwise of the pad about transverse axes, and means 55 for varying the positions of said axes lengthwise of the pad.

5. An apparatus for use in applying pressure to shoe bottoms having, in combination, a pad for 60 pressing a sole against a shoe bottom, a plurality of members for holding the pad in operative position, means separate from the pad holding members for engaging each member and supporting it for tipping movement in a vertical plane extending lengthwise of the pad, and means for adjusting said supporting means lengthwise of the pad relatively to said holding members, thereby 65 permitting said members to be tipped into different positions about said supporting means to conform the pad to the longitudinal contour of 70 the shoe bottom.

6. An apparatus for use in applying pressure to shoe bottoms having, in combination, a resilient pad for pressing a sole against a shoe bottom, separate members for holding different portions of the pad in pressure applying position, abutments 5 for supporting each of said separate members for rocking movement relatively to one another, and single means for adjusting said abutments relatively to one another lengthwise of the pad. 10

7. An apparatus for use in applying pressure to shoe bottoms having, in combination, a pad for 15 pressing a sole against a shoe bottom, separate members for holding the pad, a fulcrum for each of said holding members, and means for simultaneously adjusting said fulcrums lengthwise of the pad to vary their positions relatively to the pad holding members.

8. An apparatus for use in applying pressure to shoe bottoms having, in combination, a pad for 20 pressing a sole against a shoe bottom, a plurality of members for holding different portions of the pad, an abutment engaging each of said members and supporting it for rocking movement about an axis extending widthwise of the pad, and single 25 means for adjusting said abutments toward and from each other lengthwise of the pad.

9. An apparatus for use in applying pressure to shoe bottoms having, in combination, a pad for 30 pressing a sole against a shoe bottom, separate members for holding the forepart and the shank and heel portions of the pad, an abutment for supporting each of said members, said abutments being arranged to permit swinging movement of said members lengthwise of the pad about axes 35 extending widthwise thereof, and manually operated means for simultaneously moving said abutments lengthwise of the pad, thereby permitting the holding members to be swung about said axes to conform the pad to the longitudinal contour of 40 the shoe bottom.

10. An apparatus for use in applying pressure to shoe bottoms having, in combination, a pad for 45 pressing a sole against a shoe bottom, separate members for holding the forepart and the shank and heel portions of the pad in operative position, an abutment engaging each pad holding member and supporting it for rocking movement about an axis formed by the abutment and in a plane extending lengthwise and heightwise of a 50 shoe mounted on the pad, and single means for simultaneously adjusting said abutments in the same direction relatively to the pad.

11. An apparatus for use in applying pressure to shoe bottoms having, in combination, a pad for 55 pressing a sole against a shoe bottom, separate members for holding different portions of the pad, an abutment for supporting each holding member for rocking movement lengthwise and heightwise of the pad, and single means for adjusting said abutments simultaneously in the same or in opposite directions lengthwise of the pad to permit said pad holding members to be rocked into different angular positions about said abutments. 60

12. An apparatus for use in applying pressure to shoe bottoms having, in combination, a pad for 65 pressing a sole against a shoe bottom, separate members for holding the pad in operative position, means for supporting each of said members for rocking movement lengthwise of the pad, means for adjusting said supporting means lengthwise of the pad to vary the axes about which said members rock, thereby permitting said members to be rocked into different angular posi- 70

- tions, and means for maintaining said members in any position into which they may be rocked.
13. An apparatus for use in applying pressure to shoe bottoms having, in combination, a pad for pressing a sole against a shoe bottom, separate members for holding the forepart and the rear portions of the pad in operative position, abutments for supporting each of said members for tipping movement lengthwise of the pad about an axis extending widthwise of the pad, single means for adjusting said abutments lengthwise of the pad to permit said members to be tipped about their axes into positions which will conform the pad to the longitudinal contour of the shoe bottom, and means for frictionally holding said members in said positions until pressure is applied to the sole and shoe. 5
14. An apparatus for use in applying pressure to shoe bottoms having, in combination, a pad for pressing a sole against a shoe bottom, separate members for holding the pad in operative position, an abutment engaging each pad holding member and supporting it for swinging movement lengthwise of the pad about said abutment, and single means for simultaneously adjusting the abutments lengthwise of the pad to vary their positions relatively to the pad holding members and thereby to control the pressure applied by the pad to different portions of the sole and shoe bottom. 10
15. An apparatus for use in applying pressure to shoe bottoms having, in combination, a pad for pressing a sole against a shoe bottom, separate members for holding the forepart and the rear portions of the pad in operative position, an abutment engaging each pad holding member and providing a fulcrum for swinging movement of the member lengthwise of the pad relatively to the other pad holding member, and single means for adjusting the abutments lengthwise of the pad relatively to their pad holding members, thereby to vary the fulcrums about which said members swing and change their leverages so that the pressure applied by the pad to different portions of the sole and shoe bottom will be correspondingly varied. 15
16. An apparatus for use in applying pressure to shoe bottoms having, in combination, a pad for pressing a sole against a shoe bottom, separate members for holding the forepart and the rear portions of the pad in operative position, an abutment engaging each pad holding member and supporting it for rocking movement lengthwise and heightwise of the pad relatively to the other pad holding member, and means for simultaneously adjusting the abutments lengthwise of the pad to permit the pad holding members to be rocked into initial positions that will conform the pad to the longitudinal contour of the shoe bottom, and also to locate said abutments in such positions relatively to said members that the pressure against the forepart and rear portions of the sole and shoe bottom will be applied substantially uniformly for each unit of bottom area. 20
17. An apparatus for use in applying pressure to shoe bottoms having, in combination, a pad for pressing a sole against a shoe bottom, separate members for holding the forward and rear portions of the pad in operative position, a support, links pivotally connecting one of said members to said support, links pivotally connecting the last-named member to the other separate member, abutments movable lengthwise of the support for engaging said members and support- 25
- ing them for rocking movement lengthwise of the pad, and means for adjusting said abutments lengthwise of the pad to permit said separate members to be rocked relatively to said links into positions which will conform the pad to the longitudinal contour of the shoe bottom. 5
18. An apparatus for use in applying pressure to shoe bottoms having, in combination, a pad for pressing a sole against a shoe bottom, separate members for holding the forward and rear portions of said pad, a support, a pair of links pivotally connecting one of said separate members to the support, a second pair of links pivotally connecting the last-named member to the other separate member, abutments movable lengthwise of the support between said links for engaging said separate members and supporting them for swinging movement lengthwise of the pad about axes extending widthwise of the pad, a screw for simultaneously adjusting said abutments toward 10 and from each other lengthwise of the pad to permit said separate members to be swung into different positions about said axes to conform the pad to the longitudinal contour of the shoe bottom, and resilient means for maintaining said members in any positions into which they may be swung until pressure is applied to the sole and shoe. 15
19. An apparatus for use in applying pressure to shoe bottoms having, in combination, a pad for pressing a sole against a shoe bottom, separate members fixed against movement transversely of the pad for holding the forepart and rear portions of the pad in operative position, and means between the pad and one of said members for effecting only transverse rocking movement of the portion of the pad held by said member under pressure from the shoe to cause said portion to adjust itself automatically to the transverse angle of the portion of the shoe bottom engaged thereby. 20
20. An apparatus for use in applying pressure to shoe bottoms having, in combination, a pad for pressing a sole against a shoe bottom, separate members fixed against movement transversely of the pad for holding the forepart and rear portions of the pad in operative position, and an insert located between the pad and one of said holding members, said insert having a convex bottom surface the curve of which extends only transversely of the pad, thereby causing the portion of the pad held by said member to rock only transversely under pressure from the shoe and thus to be positioned automatically to the transverse angle of the portion of the shoe bottom engaged by said portion of the pad. 25
21. An apparatus for use in applying pressure to shoe bottoms having, in combination, a pad, separate members for holding the forepart and rear portions of the pad, means for supporting said members for rocking movement in the longitudinal median plane only of a shoe on the pad about axes extending transversely of the pad, and means between the pad and said holding members for causing the portions of the pad held by each of said members to relatively adjust themselves automatically to the transverse angles of corresponding portions of the shoe bottom as pressure is applied to the sole and shoe. 30
22. An apparatus for use in applying pressure to shoe bottoms having, in combination, a pad for pressing a sole against a shoe bottom, separate members for holding the pad, means for supporting said members for rocking movement lengthwise of the pad, means for adjusting said 35
- 70
- 75

- supporting means lengthwise of the pad, thereby permitting said members to be rocked into different positions to conform the pad to the longitudinal contour of the shoe bottom, and means 5 for causing a portion of the pad to conform itself automatically to the transverse angle of the shoe bottom.
23. An apparatus for use in applying pressure to shoe bottoms having, in combination, a pad 10 for pressing a sole against a shoe bottom, separate members for holding the forepart and rear portions of the pad, means for supporting said members for tipping movement lengthwise only of the pad, single means for simultaneously adjusting said supporting means lengthwise of the pad, thereby permitting said separate members to be tipped relatively to the supporting means to conform the pad to the longitudinal contour of the shoe bottom, and separate means for causing 15 the forepart only of the pad to adjust itself automatically to the transverse angle of the shoe bottom under pressure from the shoe.

24. An apparatus for use in applying pressure to shoe bottoms having, in combination, a pad for pressing a sole against a shoe bottom, separate members for holding the forepart and rear portions of the pad, means for supporting said members for rocking movement in a plane extending lengthwise and heightwise of a shoe on the pad, single means for simultaneously adjusting said supporting means lengthwise of the pad, thereby permitting said members to be 5 rocked in said plane into angular positions which will conform the pad to the longitudinal contour of the shoe bottom, and an insert carried by the member holding the forepart of the pad and having a bottom surface which is convex transversely of the pad whereby the forepart of the pad will be caused to adjust itself automatically to the transverse angle of the forepart of the shoe bottom under pressure from the sole and shoe. 10 15

ERASTUS E. WINKLEY.

20
